UNITED STATES PATENT OFFICE.

LOUIS CHAMBON, OF PARIS, FRANCE.

MACHINE FOR MAKING AND FILLING CIGARETTE-CASES.

1,121,549.

Specification of Letters Patent. Patented Dec. 15, 1914.

Application filed January 3, 1913. Serial No. 739,954.

To all whom it may concern:

Be it known that I, LOUIS CHAMBON, citizen of France, residing at Paris, France, have invented a new and useful Machine for 5 Making and Filling Cigarette-Cases, of which the following is a specification.

This invention relates to a machine for making and filling paper boxes, and specially cigarette cases.

10 Taken as a whole the machine comprises the combination of the following devices:— A device for first drawing from a bobbin the paper previously printed and perforated which is to serve for making the case, then 15 measuring the said paper to the correct size, then gumming it at suitable parts, and finally stretching it, while at the same time tracing or marking on it the folds along the necessary lines; a device succeeding that 20 just described for cutting and folding the paper for the purpose of constructing the case without immediately closing the latter, so as to leave it ready to receive the articles, 25 cigarettes for example, with which it is to be filled. The said machine is generally combined with another apparatus not described in details in the present specification because it forms the subject matter of my divisional application, Serial Number 30 828,531, filed March 31, 1914. The said apparatus includes several devices having for their purposes to receive the cases made by the aforesaid machine, to distribute the articles, cigarettes for example, into the cases, 35 to gum and close the finished and filled cases, and finally to receive and distribute the filled cases.

A machine constructed in accordance with the invention is shown by way of example 40 in the accompanying drawings.

Figure 1 is a side elevation of the whole of the machine. Fig. 2 is a vertical section on the longitudinal axis of the machine of the device for cutting and folding the paper 45 from which the cases are made. Fig. 3 is a view in horizontal plane, of the said device. Fig. 4 a view in elevation in a vertical plane at right angles to the longitudinal axes, of the machine of the said device.

50 The same reference numerals indicate the same parts in the several figures.

The whole machine is represented dia-

grammatically in Fig. 1, wherein A is the bobbin of paper previously printed and provided with suitable guide perforations on 55 its edges, the said perforations being placed in accordance with the disposition of the impressions wherewith the paper is furnished; B, the apparatus for drawing the paper band from the aforesaid bobbin, and 60 for delivering the said paper band in successive blanks, exactly in conformity with the impressions which are traced on the paper, and which are destined to illustrate, at determined places, the faces or the sides of 65 the finished cases; C, the apparatus for gumming the said paper band at suitable places and D the apparatus for stretching the paper and marking the folds. These apparatus are themselves known and are not 70 referred to herein otherwise than as constituent parts of the machine.

Following the stretching and marking apparatus D is the device E for cutting and folding the paper which is of an improved 75 kind and will presently be described in detail with reference to Figs. 2, 3 and 4.

When they have left the device E, the cases are received by a wheel F, and the articles, cigarettes for example, are now distributed and introduced into the cases made by the preceding apparatus, by means of a device G; finally the finished and filled cases are gummed and glued by a device H, and the closed cases are transferred into a distributing box I, at the discharge end of 80 which they are received by the operative.

Relating to the improved apparatus E for cutting and folding the paper, of which the cases are made, and referring to Figs. 2, 3 90 and 4, the apparatus is driven, like those which precede it, from the longitudinal shaft of the machine through the intermediary of two worm gears 1, the shafts of which are coupled by direct gear, such as 95 1', 1', 1''. The matrices 2, 3 and 4 provided for the cutting of the paper are firmly fixed on the metal table 5 which forms at the same time a tie bar for the cheeks of the frame of the machine. The stamping punches 100 which are to co-act with the aforesaid matrices are mounted on a plate 6, which is moved up and down by the four eccentrics 7 keyed on the shafts 8 and 9, these shafts be-

ing driven by the transmission gear 1', 1'' aforesaid. These eccentrics are coupled in pairs by tie bars 7' and move up and down four slides 10 guided in the cheeks 10' of the frame, and tied together at their upper parts by tie bars 11 and 12 to which is fixed the plate 6 carrying the punches. The plate 6 carries near the tie bar 12 two spring pistons 13 for the purpose of stopping the paper during the stamping and folding operations. The tie bar 11, carries a spring presser 14 and fixed blades 15 which serve to fold the sides of the case as will presently be explained.

15 The spring pistons 13 serve to hold the paper at the desired moment when the plate 6 descends, the paper being at that time stretched by the drawing rollers or wheels 16, 17 and applied to a forming block 18 by means of the upper spring presser 14. At this moment the blade 19, constituting the end folder and mounted on a lever 20 adapted to oscillate on a shaft 20' under action of cam levers 21, connecting rod 21' and cams 22, folds the paper on the block 18 successively to give it corresponding forms. The lower spring presser 23 is then raised by cam levers 24, connecting rods 24' and cams 25 and holds on the lower face of the block 18 the paper which has been folded in the manner described. A piece 26, which is raised at the same time as the spring presser 23 under action of a pusher 27 actuated by the aforesaid connecting rods, continues further its ascending movement and then folds by means of blades 28, which it carries, the short lower sides of the case on the block 18; at the same time the tie bar 11 continues its descending movement and completes the folding by means of blades 15, which fold then the two short upper sides of the case. As soon as the short sides of the case have been folded in the manner just described, two jaws 29 carried by cam levers 30, oscillating on shafts 30' under action of cams 31, press firmly against the faces of the block 18 the folded sides of the case so as to insure a satisfactory sticking of these sides together. At the end of the folding operations above detailed, the part of the paper which constitutes the case is separated from the rest of the paper band by means of a cutter 32 which cuts the paper along the gap 18' between the block 18 and the matrix 4 already specified; at the same time the cutters 33, 34, carried by the plate 6, cut on the paper band the slots necessary for making the case. The cutting and folding operations so far described being finished, the lower spring presser descends again, while the plate 6, carrying the cutters, ascends, thereby liberating the upper presser 14. The end folder 19 also returns to its original position, disengaging the

block 18 so as to allow the finished case to go forward as will presently be explained. On the other hand the lifting of plate 6 also disengages the spring piston 13 so that the paper band is drawn forward to the extent required for a fresh operation by the rollers 16, 17. Roller 16 is driven for this purpose intermittently by a cam lever 35 keyed on shaft 8 and operating in the usual manner a Maltese cross 36, on the axle of which is mounted a toothed wheel 16' driving through the gears 16'', 16''' the shaft on which the roller 16 is keyed. The operations which have been described so far are periodically performed, in the order named. The finished cases are then received in the device F, and filled, gummed, glued and finally distributed through the devices G, H, I, above specified.

Having thus described my invention and the best means I know of carrying the same into practical effect I claim:

1. A machine for making paper boxes or cases by folding the paper on a fixed forming block, the said machine comprising in combination, a support for a bobbin of paper band previously printed, and provided on its edges with suitable guide perforations, corresponding to the position of the impressions wherewith the paper is furnished; a device for drawing the said paper band and delivering this latter in successive blanks, exactly in conformity with the impressions traced on the paper; a device for gumming the paper band at suitable places; a device for stretching the paper band and marking on this latter the folds along the necessary lines corresponding to the parts to be subsequently folded on the fixed forming block; and an apparatus succeeding the last named device; the said apparatus including devices for cutting the paper band and for folding and suitably sticking together the several parts of the paper on the fixed forming block, in order to obtain an open case ready to receive articles to be packed.

2. In a machine for making paper boxes or cases, an apparatus for cutting and folding the paper into the form of the box or case to be manufactured, the said apparatus comprising rollers, spring pressers adapted to hold the paper drawn by the action of the said rollers, matrices, cutters co-acting with the said matrices to cut the slits necessary for the folding of the sides of the case and for cutting the paper along the contour of the folding flap of the said case, a forming block, an upper spring presser adapted to apply a part of the paper against the said block, an end folder adapted to fold another part of the paper beneath the said block, a lower spring presser adapted to hold the paper thus folded beneath the block, lower

and upper lateral blades adapted to fold against the sides of the block first the short lower sides of the case and then the short upper sides thereof, and two lateral jaws 5 adapted to press the said short folded sides against the said block for the purpose of insuring proper gumming.

In testimony whereof I have signed my name to this specification in the presence of two subscribing witnesses.

LOUIS CHAMBON.
